(57) **CLAIM**

The ornamental design for an automatic hair styling device, as shown and described.

DESCRIPTION

FIG. 1 is a front perspective view of an automatic hair styling device according to the new design;

FIG. 2 is a front elevation view of the automatic hair styling device shown in FIG. 1;

FIG. 3 is a side view of the automatic hair styling device shown in FIG. 1;

FIG. 4 is a rear view of the automatic hair styling device shown in FIG. 1;

FIG. 5 is a top plan view of the automatic hair styling device shown in FIG. 1; and,

FIG. 6 is a bottom plan view of the automatic hair styling device shown in FIG. 1.

The broken lines illustrate portions of the automatic hair styling device and form no part of the claimed design.

1 Claim, 5 Drawing Sheets
